UNITED STATES PATENT OFFICE.

HOWARD H. HUMMEL, OF BETHLEHEM, PENNSYLVANIA, ASSIGNOR TO BETHLEHEM STEEL COMPANY, OF BETHLEHEM, PENNSYLVANIA, A CORPORATION OF PENNSYLVANIA.

HYDRAULIC PRESS.

Application filed March 8, 1922. Serial No. 542,190.

To all whom it may concern:

Be it known that I, HOWARD H. HUMMEL, a citizen of the United States, residing at Bethlehem, Pennsylvania, have invented certain new and useful Improvements in Hydraulic Presses, of which the following is a specification.

This invention relates to a press which is particularly adapted for making compressed 10 paper rolls or cylinders.

Paper rolls of the kind in question are made by pressing annular sheets of paper together to form a thick walled cylinder of considerable length and it is necessary that the material forming the roll be made dense and homogeneous throughout. To insure homogeneity the paper rolls are built up in stages, that is, a number of annular sheets of paper are threaded on a mandrel and 15 compressed after which successive batches or supplies of annular sheets are added and compressed until the roll is built up to the desired length. It is the object of this invention to provide a press which can be easily and rapidly manipulated and which will facilitate the operations necessary between the several pressings during the manufacture of such rolls. Preferably hydraulic means are employed for operating the press.

30 In the accompanying drawings forming part of this specification there is illustrated one specific embodiment of the invention. In said drawings:

Figure 1 is a front elevation of the press; 35 Figure 2 is a vertical sectional view substantially on the line 2—2 of Figure 1;

Figure 3 is a plan view of the press; and

Figure 4 is a sectional view substantially 40 on the line 4—4 of Figure 1, certain parts being shown cut away.

Referring to the drawings in detail, 10 indicates the base of the press which is secured in position in any desired manner. The base 10 is centrally bored to receive a 15 ram or plunger 11 beneath which fluid from any suitable source may be supplied for the purpose of elevating the plunger and the parts attached thereto. A platform 12 is bolted to the upper end of the plunger 11, 20 this platform having a forwardly extend-

ing portion 12^a. A table or support 13 is slidably mounted on the platform 12, this platform and the extension 12^a thereof being provided with guide ways 14 in which the table 13 is adapted to slide. 55

For moving the table back and forth in its guideways the following means are provided. At each edge the table 13 is bored longitudinally to form cylinders 15, within which stationary plungers 16 are mounted, 60 these plungers at their outer ends being rigidly secured to the platform 12. A passage is formed in each of the plungers 16, which passages extend the entire length of the plungers and communicate at their outer 65 ends with a pipe 18 for supplying pressure fluid to the cylinders 15. The table 13 is also provided substantially at its center with a longitudinally extending cylinder 19 which is adapted to receive a stationary 70 plunger 20, the latter being rigidly secured to the extension 12^a of the platform 12. The plunger 20 also has a passage extending throughout its entire length by which pressure fluid is supplied to the cylinder 19, this 75 passage communicating with a pipe 21 for supplying pressure fluid.

The cylinders 15 and 19 are preferably made of the same size and receive pressure fluid from a common source. The cylinder 80 19 is preferably supplied with pressure fluid at all times which serves to hold the table 13 normally in its inner position. When pressure fluid is supplied to the cylinders 85 15 the constant pressure in the cylinder 19 is overcome and the table is moved to its outer position. When the pressure within the cylinders 15 is relieved the table will be automatically returned to its position above the plunger 11 by means of the constant 90 pressure maintained in the cylinder 19. The details of the system for supplying the pressure fluid and of the valve mechanism for controlling the supply of such pressure fluid to the plunger 11 and to the cylinders 15 95 and 19 are not illustrated as these may be of any approved type and arranged in any convenient position. A desirable arrangement for supplying pressure fluid to the cylinders 15 and 19 is shown in the drawing in 100

which the pipes 18 and 21 are connected, respectively, to pipes 18^a and 21^a which receive pressure fluid from the cylinders 18^b and 21^b through which they slide.

5 A block or foot-step 25 is bolted to the upper surface of the table 13, this block, as shown particularly in Figure 4, having a U-shaped recess or opening parallel to the length of the table 13.

10 To receive the annular sheets of paper which are to form the roll a mandrel 26 is mounted on the block 25, the lower end of the mandrel extending into the U-shaped recess of the block. Generally the mandrel on which the roll is formed is subsequently used as the shaft for the finished roll, and as shown in the drawings, the mandrel 26 is provided at its lower end with an annular plate 27 which is pressed thereon and which rests upon the top of the block 25, and against which the paper is compressed in forming the roll.

A plurality of vertical columns 30 are 25 fixedly supported in any suitable manner in the base 10, preferably three of these columns being employed. The upper ends of these columns are held in rigid relation by means of a spider 31 secured thereto. 30 The columns 30 are threaded at their upper ends for a considerable distance and such threaded portions are engaged by threaded bushings or nuts 32 which are suitably journaled in a cross head 33. Each of said 35 bushings 32 at its upper end is provided with a worm wheel 34 suitably secured thereto which worm wheels are arranged to mesh with worms 35 secured to shafts 36, journaled in suitable bearings on the cross 40 head 33. These shafts are rotated in any suitable manner as by means of a reversible motor 37 connected to a shaft 38 provided with worms 38^a meshing with worm wheels 36^a on the shafts 36. It will be apparent 45 from the foregoing that when the threaded bushings 32 are rotated by means of the motor 36 the cross head 33 will be caused to move toward or from the table 13.

When the table 13 is moved along the 50 guideways 14, as heretofore described, the mandrel 26 mounted thereon, will, of course, be moved with the table. In other words, the mandrel will be moved in a direction transverse to its own axis, or laterally of 55 the cross head 33. To permit such lateral movement of the mandrel the cross head 33 is provided with a U-shaped slot or opening 40 as will clearly appear from Figures 1 and 2 of the drawings. This slot or 60 opening 40 is arranged parallel to the direction of movement of the table 13 so that when the table is moved outwardly the mandrel can pass through the opening 40 to a position beyond the cross head 33.

65 During the operation of compressing the

paper it is desirable to place an annular plate similar to the plate 27 upon the upper end of the mandrel and such a plate is indicated at 27^a on the drawing. If desired, the cross head 33 may also be provided with a block 33^a similar to block 25 for bearing against the plate 27^a.

In operation, assuming the cross head 33 in its upper position and the table 13 in its outer position, a mandrel, such as 26, 75 is mounted centrally on the latter, the lower end of the mandrel extending into the U-shaped opening of the block 25 and the plate 27 resting upon this block. A quantity of paper rings are now threaded on the mandrel and the metal plate or ring 27^a is placed on top of the paper rings. The fluid pressure in the cylinders 15 is then released when the constant pressure in the cylinder 19 causes the table to move automatically to 80 its inner position beneath the cross head 33. The motor 37 is then started in a direction to lower the cross head until its lower face or the block 33^a secured thereto rests on the plate 27^a supported by the 85 paper rings. At such time the mandrel 26 projects upwardly in the slot or opening 40 of the cross head 33. Fluid pressure is then applied under the ram or plunger 11 to raise the table 13 and, as a result, the 90 paper rings are pressed together between the rings 27 and 27^a surrounding the mandrel. The pressure under the ram 11 is held for a short time and is then released to lower the table 13. The latter is then 95 moved to its outer position by supplying pressure fluid to the cylinders 15 during which movement the upper end of the mandrel passes through the U-shaped opening 100 105 40 of the cross head 33 until it is free from the cross head. The next batch of paper rings are now threaded on the mandrel, the metal ring 27^a in the meantime being removed. During the operation of threading the new supply of rings on the mandrel the motor 37 is started to raise the 110 cross head sufficiently to clear the second batch of rings. The operations are repeated 115 until the required length of paper roll is obtained.

By constructing the cross head as described, it will be understood that the mandrel can be moved laterally to a position clear of the cross head, and it is, therefore, unnecessary to move the latter upwardly 120 to clear the upper end of the mandrel. When the mandrel and the table 13 are moved to their outer position the cross head and the columns supporting the same do not interfere in any way with the threading 125 of the paper disks on the mandrel and while such operation is proceeding the cross head can be returned to its normal position at the top of the columns. The entire construction, therefore, is so arranged as to 130

facilitate the operations incident to forming the rolls or cylinders.

What I claim as my invention and desire to secure by Letters Patent is:

5 1. In a machine of the kind described, in combination, a mandrel, a movable support on which one end of the mandrel is mounted and means for moving said support and mandrel in a direction parallel to the axis of the mandrel and also in a direction transverse to said axis.

10 2. In a machine of the kind described, in combination, a support adapted to receive a mandrel, a cross head, and means for moving said support toward and from said cross head and also transversely of said cross head.

15 3. In a machine of the kind described, in combination, a support adapted to receive a mandrel, a cross head, means for moving said support toward and from said cross head and also transversely of said cross head, and means for moving said cross head toward and from said support.

20 25 4. In a machine of the kind described, in combination, a mandrel, a movable support on which one end of the mandrel is mounted, a cross head, means for moving said support and mandrel toward and from said cross head, said cross head having a slot or opening extending inwardly from one side thereof and adapted to receive said mandrel, means for moving said support and mandrel in a direction transverse to the axis of the mandrel whereby the mandrel is moved through said slot or opening in said cross head.

25 30 40 45 50 5. In a machine of the kind described, in combination, a mandrel, a movable support on which one end of the mandrel is mounted, a cross head, means for moving said support and mandrel toward and from said cross head, said cross head having a slot or opening extending inwardly from one side thereof and adapted to receive said mandrel, means for moving said support and mandrel in a direction transverse to the axis of the mandrel whereby the mandrel is moved through said slot or opening in said cross head, and means for moving said cross head toward and from said support.

35 40 45 50 55 60 65 6. In a machine of the kind described, in combination, a support adapted to receive a mandrel, a cross head having a slot or opening extending inwardly from one side thereof, means for moving said support transversely of said cross head and in a direction parallel to said slot or opening, and means for moving said support toward and from said cross head.

7. In a machine of the kind described, in combination, a support adapted to receive a mandrel, a cross head having a slot or opening extending inwardly from one side thereof, means for moving said support trans-

versely of said cross head and in a direction parallel to said slot or opening, means for moving said support toward and from said cross head, and means for moving said cross head toward and from said support.

70 8. In a machine of the kind described, in combination, a support adapted to receive a mandrel, a cross head having a slot or opening extending inwardly from one side thereof, means for moving said support transversely of said cross head and in a direction parallel to said slot or opening, and means for moving said cross head toward and from said support.

75 80 85 90 9. In a machine of the kind described, in combination, a cross head, a support arranged beneath said cross head, a mandrel mounted on said support and extending upwardly therefrom, means for moving said support and mandrel in a direction transverse to the axis of the mandrel, said cross head having a slot or opening to permit such transverse movement of the mandrel, and means for moving said support and mandrel toward and from said cross head.

95 10. In a machine of the kind described, in combination, a cross head, a support arranged beneath said cross head, a mandrel mounted on said support and extending upwardly therefrom, means for moving said support and mandrel in a direction transverse to the axis of the mandrel, said cross head having a slot or opening to permit such transverse movement of the mandrel, and means for moving said cross head toward and from said support.

100 105 110 115 120 125 130 11. In a machine of the kind described, in combination, a support having a mandrel mounted thereon and extending upwardly therefrom, means for moving said support transversely of the axis of the mandrel, a cross head arranged above said support, means for moving said cross head toward and from said support, said cross head having a slot or opening adapted to receive the upper end of the mandrel, said slot being arranged parallel to the direction of movement of said support whereby the mandrel may be moved through such slot during transverse movement of said support.

12. In a machine of the kind described, in combination, a base, a plurality of standards extending upwardly therefrom, a cross head carried by said standards, a support arranged below said cross head, a mandrel carried by said support and extending upwardly toward said cross head, means for moving said support and mandrel in a direction transverse to the axis of said mandrel, and means for moving said cross head toward and from said support.

13. In a machine of the kind described, in combination, a platform, hydraulic means for operating the same, a table slidably supported on said platform and movable lat-

erally of the same, and a cross head arranged above said table and movable toward and from the same.

14. In a machine of the kind described, in combination, a base, a plurality of standards extending upwardly therefrom, a cross head carried by said standards, a table arranged beneath said cross head and adapted to support a mandrel, means for moving said cross head along said standards toward and from said table, means for moving said table and mandrel toward and from said cross head and laterally thereof, said cross head having a slot therein to permit lateral movement of the mandrel when the table is moved laterally of the cross head.
15. In a machine of the kind described, in combination, a base, a plurality of threaded standards extending upwardly from the base, a cross head having a plurality of threaded bushings engaging said standards, means for rotating said bushings whereby said cross head is caused to move along said standards, a table arranged beneath said cross head and movable toward and from the same.

16. In a machine of the kind described, in combination, a base, a plurality of threaded standards extending upwardly from the base, a cross head having a plurality of threaded bushings engaging said standards, means for rotating said bushings whereby said cross head is caused to move along said standards, a table arranged beneath said cross head and movable toward and from the same, and means for moving said table laterally of said cross head.

17. In a machine of the kind described, in combination, a base, a plurality of threaded standards extending upwardly from the base, a cross head having a plurality of threaded bushings engaging said standards, means mounted on the cross head for rotating said bushings whereby said cross

head is caused to move along said standards, a table arranged beneath said cross head and movable toward and from the same, and means for moving said table laterally of said cross head.

18. In a machine of the kind described, in combination, a base, a plurality of threaded standards mounted thereon, a cross head carried by said standards, a plurality of bushings rotatably mounted in said cross head and threadedly engaging said standards, means mounted on said cross head for rotating said bushings whereby said cross head is caused to move along said standards, a support for a mandrel arranged beneath said cross head, said cross head having a slot extending inwardly from one side thereof whereby the mandrel mounted on said support may be moved laterally of the cross head when the cross head is moved to a position below the upper end of the mandrel.

19. In a machine of the kind described, in combination, a base, a plunger mounted therein, a table supported by said plunger, a mandrel supported on said table and extending upwardly therefrom, a plurality of threaded standards extending upwardly from said base, a cross head carried by said standards, means for raising and lowering said plunger to move said table toward and from said cross head, means mounted on said cross head and engaging said standards for moving the cross head toward and from said table, means for moving said table laterally of said cross head, said cross head having an opening adapted to receive the upper end of said mandrel, said opening extending laterally to the edge of said cross head, whereby lateral movement of the mandrel is permitted when the upper end thereof extends into the cross head.

In testimony whereof I hereunto affix my signature.

HOWARD H. HUMMELL.
